UNITED STATES PATENT OFFICE

160,185

EXPANSIBLE CHAIN FOR A BRACELET OR SIMILAR ARTICLE

Paul Levinger, Providence, R. I., assignor to Speidel Corporation, Providence, R. I., a corporation of Rhode Island

Application April 21, 1950, Serial No. 9,397

Term of patent 14 years

(Cl. D45—4)

To all whom it may concern:

Be it known that I, Paul Levinger, a citizen of the United States of America, residing at Providence, county of Providence, and State of Rhode Island, have invented a new, original, and ornamental Design for an Expansible Chain for a Bracelet or Similar Article, of which the following is a specification, reference being had to the accompanying drawing, forming a part thereof.

Fig. 1 is a top plan view of an expansible chain embodying my new design with the links in contracted position;

Fig. 2 is a view similar to Fig. 1 with the links in an expanded position, portions of the conventional appearing bottom links being visible between the expanded top links;

Fig. 3 is a top plan view of a single top link of the expansible chain; and

Fig. 4 is an edge elevational view looking from right to left at the link shown in Fig. 3.

I claim:

The ornamental design for an expansible chain for a bracelet or similar article, substantially as shown.

PAUL LEVINGER.
